UNITED STATES PATENT OFFICE.

JOHN E. MILLER, OF WASHINGTON, PENNSYLVANIA, ASSIGNOR TO GEO. DUNCAN'S SONS & CO., OF SAME PLACE.

DESIGN FOR A GLASS VESSEL.

SPECIFICATION forming part of Design No. 24,276, dated May 7, 1895.

Application filed March 26, 1895. Serial No. 543,286. Term of patent 8½ years.

To all whom it may concern:

Be it known that I, JOHN E. MILLER, of Washington, in the county of Washington and State of Pennsylvania, have invented a new and original Design for Glass Vessels, of which the following is a full, clear, and exact description.

The accompanying drawing shows in side elevation a glass vessel provided with my design.

The design consists in a glass vessel having thereon a surface pattern comprising diamond-shaped figures made up of series of adjacent similar and symmetrical projections, said diamond-shaped figures being surrounded by marginal bands constituted by series of broad serrations, and the angular spaces be-

tween the diamond figures being filled in with fan-shaped patterns constituted of grooves radiating from the apices of the angles. 20

In the drawing, 2, 2, represent the diamond-shaped figures above mentioned; 3, 3, the marginal bands composed of series of broad serrations; and 4, 4, the fan-shaped figures set in the angular spaces between the bands. 25

I claim—

The design for glass vessels substantially as herein shown and described.

In testimony whereof I have hereunto set my hand.

JOHN E. MILLER.
